UNITED STATES PATENT OFFICE.

PETER A. JUUL, OF CHICAGO, ILLINOIS, ASSIGNOR TO LATHAM MACHINERY COMPANY, A CORPORATION OF ILLINOIS.

FEED GAUGE.

Application filed September 12, 1924. Serial No. 737,305.

This invention relates to a feed gauge and is more particularly adapted for use in connection with perforating machines.

One of the objects of the present invention 5 is to provide an improved feed gauge, which is simple in construction and efficient in operation.

A further object of the invention is to provide an adjustable feed gauge which can be 10 quickly and easily changed to meet various requirements.

A still further object of the invention is to provide a device of the class described, which will operate with the least possible effort on 15 the part of the operator.

These and other objects are accomplished by providing a construction and arrangement of the various parts in the manner herein- 20 after described, and particularly pointed out in the appended claims.

Referring to the drawings—

Fig. 1 is a top plan view of my improved feed-gauge;

Fig. 2 is a cross sectional view taken on the 25 lines 2—2 of Fig. 1;

Fig. 3 is an enlarged fragmentary cross sectional view taken on the lines 3—3 of Fig. 1.

Fig. 4 is an enlarged fragmentary top plan 30 view of the guiding member or carriage; and

Fig. 5 is a cross sectional and side elevational view of the construction shown in Fig. 4.

The invention, in the present instance, is 35 directed to a feed gauge, which is particularly adapted for use in connection with the intermittent feeding of pre-determined lengths of paper or the like to a machine such, for instance, as a perforating machine, so that the paper so fed is perforated at predetermined 40 intervals.

The present invention is particularly useful in connection with the perforation of bank checks and the like where the checks are arranged on large sheets of paper, and are perforated from each other so that each check 45 may be readily torn from the remaining checks on the sheet.

In carrying out the present invention, I 50 have shown my improved feed gauge being mounted on a base 10, which is preferably made of wood for the purpose of lightness, but which might well be made of any material, such, for instance, as aluminum or other metals. The base 10 is substantially square 55 in outline, and is provided, on one side there-

of, with a recess 11 to accommodate the operator. Positioned on the opposite sides of the base 10 adjacent the outer edges thereof and extending longitudinally with respect thereto are flat metal strips 12, which are secured thereto by wood screws 13. Extending along the metal strips 12 and secured thereto by means of rivets 14 and slightly overhanging the inner edges thereof are longitudinal tracks 15.

Positioned on the opposite sides of the feed gauge and secured to the metal strips 12 by means of brackets 16 are two longitudinally extending bars 17. These bars 17 are square in cross-section, and are detachably secured in 70 horizontally disposed apertures 18 in the brackets 16 by means of set screws 19. Mounted on the square bars 17 are a plurality of stops 20, which are adapted to be adjusted longitudinally of the bar. These stops are 75 adapted to be locked in predetermined positions of adjustment by set screws 21, which extend through these stops in a manner to clamp the stops to the bar 17.

Mounted on the tracks 15 by means of 80 rollers is a carriage or guiding member 22. The carriage or guiding member comprises a transversely extending sheet supporting member 23 having its forward edge beveled, as shown at 24. The carriage is mounted on 85 the tracks in such a manner so that the sheet supporting member is slightly positioned above the base 10 in order to permit the same to be freely moved back and forth in the tracks without engaging the same. The sheet 90 supporting member 23 has secured on the outer ends thereof by means of screws (not shown) roller brackets 25. The outer ends of the roller brackets 25 are provided with horizontally rotating rollers 26, which are adapt- 95 ed to engage the inner edges of the tracks 15.

These rollers 26 are spaced a considerable distance apart so as to properly guide the carriage in a line substantially parallel to the track. One of the roller brackets 25 is provided with two vertically rotatable rollers 27, which are positioned adjacent the rollers 26, and are adapted to engage the upper surface of one of the tracks 15, while the other roller bracket 25 is provided with a single vertically rotatable roller 28, which is positioned adjacent the forward roller 26, and adapted to engage the upper surface of the other track 15.

The object of providing the two rollers 27 on one side thereof, and the single roller 28 110

on the other side thereof, is to permit the carriage to operate in the event the base, which in the present invention is made of wood, warps. In other words, in the event the base 10 should warp and if two rollers were provided on the opposite sides thereof, the device would become inoperative, because the carriage would bind by reason of this warping.

The roller brackets are provided, on the 10 outer sides thereof, with sockets 29, which are adapted to receive and have reciprocally mounted therein pawls 30. The pawls 30 are normally pressed outwardly by extension springs 31 engaging shoulder 32 of the pawl 15 30 at one end thereof, and engaging the base of the sockets 29 at the other end thereof. The pawls 30 are provided with inwardly projecting stem portions 33, which have vertical apertures, as shown at 34. The pawls 20 30 are provided with bevelled portions, as shown at 35, which are adapted to engage bevelled portions 36 of the stops 20 when the carriage is moved forwardly, and when the carriage is moved rearwardly the rearward faces 37 of the pawls 30 are adapted to engage 25 the forward faces 38 of the stops 20. The pawls 30 are actuated or withdrawn from their outermost position by hand operating levers 39', which are mounted on cranks 39 30 pivoted by means of a shoulder screw 41 to a reinforcing bar 42, which, in turn, is secured to the sheet supporting member 23 in any well known manner.

In order to properly position the paper so 35 that the edges thereof will be parallel with the track or the movement of the carriage, I have provided an aligning bar 41' which is adjustly secured to the member 23 by means of screws 42'. The levers 39' are each connected to the pawls 30 by means of a connecting rod 43. In order to prevent my carriage 22 from being entirely disengaged from the track in its movement, I have provided stops 44 secured to the opposite ends of the strips 40 45 12, as clearly shown in Figs. 1 and 2.

In the operation of the above described device, it will, of course, be understood that the stops 20 are positioned at desired intervals, or at the intervals at which it is desired to 50 perforate the paper, and secured in these positions by set screws or bolts 21. When this is done the paper to be perforated is positioned on the sheet or paper carrying member 23, with the edges thereof engaging the 55 front edges of the bar 41' and held thereon by the hand of the operator. When in this position the carriage is held so that the faces 37 of the pawls 30 engage the faces 38 of the first stops 20. When in this position the 60 perforating machine is then actuated by the control lever of the operator. After the first perforations have been made in the paper the carriage is pushed forwardly by the operator past the next forward adjacent stops. In 65 the passing of the next stops forwardly it will

be noted that the beveled surfaces 35 of the pawls 30 engage the beveled surfaces 36 of the stops 20 and cause these pawls to snap after passing these stops. As soon as the pawls snap, or are forced to their outermost 70 position, the carriage is then drawn backwardly so that the faces 37 of the pawls 30 engage the forward faces 38 of the stops just previously passed, and then the perforating machine is again thrown into operation to 75 perforate the next set of perforations.

This operation is continued until the sheets have been completely perforated, and then the carriage may be withdrawn to its rearmost position by actuating the levers 39' inwardly, and thereby drawing the pawls 30 inwardly against the tension of their extension springs 31, thereby permitting the carriage 22 to be withdrawn to its rearmost position. 80

From the above description it will, of 85 course, be understood that additional stops 20 may be added if necessary, and that these stops may be positioned along their respective bars 17 in such a manner that any interval between the perforations may be had. 90

From the above it will be noted that I have provided a very simple and efficient feed gauge, and one which may be adjusted to meet various requirements.

It will also be noted that I have provided 95 a device which will insure accurate and parallel perforations of the sheets of paper placed on the carriage.

And furthermore, I have provided a device 100 which will not bind, but, on the contrary, will operate with great facility and ease.

While in the above specification I have described one embodiment which my invention may assume in practice, it will, of course, be understood that the same is capable of modification, and that modification may be employed without departing from the spirit and scope of my invention as expressed in the 105 following claims.

What I claim as my invention and desire to 110 secure by Letters Patent is:

1. A feed gauge for feeding paper predetermined lengths intermittently comprising a base, tracks mounted on the opposite sides of said base, a guiding member mounted on said tracks for longitudinal movement, and horizontally and vertically rotatable rollers carried by said guiding member and engageable with said tracks for guiding and maintaining the movement of said guiding member parallel to said tracks. 115

2. A feed gauge for feeding paper predetermined lengths comprising a base, tracks mounted on the opposite sides of said base, a guiding member mounted on said tracks, a plurality of stops mounted on the opposite sides of said base, spring pressed pawls carried by said guiding member and engageable with said stops for stopping said guiding member in predetermined positions, and 120 125 130

means adjacent the central portion of said guiding member for withdrawing said pawls from engagement with said stops.

3. A feed gauge for feeding paper predetermined lengths comprising a base, tracks mounted on the opposite sides of said base, a guiding member mounted on said tracks, a plurality of stops mounted on the opposite sides of said base and projecting inwardly toward the center thereof, pawls carried by said guiding member and engageable with said stops for stopping said guiding member in predetermined positions, and means whereby said pawls may be withdrawn inwardly from engagement with said stops so that the guiding member may be returned to its rearmost position.

4. A feed gauge for feeding paper predetermined lengths intermittently comprising a base, tracks mounted on opposite sides of said base, a guiding member mounted on said tracks for longitudinal movement thereon, a plurality of rollers transversely disposed with respect to each other carried by said member and engageable with said tracks for guiding and maintaining the movement of said member parallel to said tracks, a plurality of ad-

justable stops positioned at opposite sides of said base, and yieldable means carried at opposite ends of said member and cooperable with said stops for limiting the movement of said member.

5. A feed gauge for feeding paper predetermined lengths intermittently comprising a base, tracks mounted on opposite sides of said base, a guiding member mounted on said tracks for longitudinal movement thereon, a plurality of rollers transversely disposed with respect to each other carried by said member and engageable with said tracks for guiding and maintaining the movement of said member parallel to said tracks, a plurality of adjustable stops positioned at opposite sides of said base, retractable pawls carried at opposite ends of said member and engageable with said stops for limiting the movement of said member, and manually actuated means mounted on said member adjacent the central portion thereof for retracting said pawls from engagement with said stops.

In testimony whereof I have signed my name to this specification, on this 25th day of August A. D. 1924.

PETER A. JUUL.
